Specification for Design.

Patented Apr. 13, 1920.

Application filed July 21, 1919. Serial No. 312,461. Term of patent 14 years.

To all whom it may concern:

Be it known that I, EDISON G. HULSE, a citizen of the United States, residing at No. 51 Hamilton avenue, in the city of Akron, county of Summit, and State of Ohio, have invented a new, original, and ornamental Design for Rubber Tires, of which the following is a specification, reference being had to the accompanying drawings, forming a part thereof.

Figure 1 is a top plan view of a fragment of an outer casing for pneumatic tires showing my design thereon.

Fig. 2 is a sectional view of a fragment thereof.

I claim—

The ornamental design for a rubber tire as shown.
